LICENSE PLATE FRAME

John A. Bott, 931 Lake Shore Drive,
Grosse Pointe Shores, Mich. 48236

Filed June 6, 1966, Ser. No. 2,583

Term of patent 14 years

(Cl. D14—6)

FIGURES 2 and 3 are top and side views thereof; and

The dominant features of my design reside in the portions shown by means of full lines, said features being characterized by the depressed grooves and raised ridges on either side of the contrasting color area, as best seen in FIGS. 1 and 4.

I claim:

The ornamental design for a license plate frame, substantially as shown and described.
